EMIL PFIFFNER, OF FRIBOURG, SWITZERLAND, ASSIGNOR, BY MESNE ASSIGNMENTS, TO RADIO PATENTS CORPORATION, OF NEW YORK, N. Y., A CORPORATION OF NEW YORK

ARRANGEMENT OF DISCHARGE SPARK GAPS ON ELECTRIC CONDENSERS

Application filed December 16, 1925, Serial No. 75,858, and in Germany November 24, 1924.

This invention relates to improvements in the arrangement of discharge spark-gaps on electric condensers of the type referred to in my prior Patent No. 1,529,712 and copending application Serial Number 75,859, filed December 16, 1925, in order to automatically protect the same against punctures by temporary boosting voltages.

Electric condensers in which the dielectric is subjected to great electric stress, are in danger of disruption or punctures in the event of temporary boosting voltages, such as may arise, for different reasons, in electric circuits.

According to the present invention the arrangement of discharge spark-gaps employed in connection with electric condensers consists in that an automatically quenching or extinguishing discharger, comprising one or more discharge spark-gaps, is immovably mounted in a hollow space of the condenser in series with one or more damping resistances and connected between the two poles of the condenser.

The hereinafter described arrangement of discharge spark-gaps in condensers is formed by dielectric layers and conducting coatings wound in the form of a hollow cylinder and in which, in the event of condensers connected in series (compound condenser), each condenser is furnished with a complete discharge arrangement, comprising one or a number of discharge spark-gaps with damping resistances. The damping resistances in series with the discharge spark-gap cause a dead-beat discharge of the boosting voltage parallel to the electric condenser.

Two modes of carrying out the present invention are illustrated in sectional elevation and by way of example on the accompanying sheet of drawings.

Fig. 1 is a central vertical sectional view more or less diagrammatic, of a condenser unit adapted to be employed in connection with the invention.

Fig. 2 is a view similar to Fig. 1 but showing a plurality of such units assembled in series.

Fig. 3 is a view similar to Fig. 1 but illustrating a somewhat modified arrangement of conducting and dielectric sheets, and

Fig. 4 is a diagrammatic cross sectional view of the arrangement of dielectric and conducting sheets shown in Fig. 3.

The electric condenser shown in Fig. 1 consists of dielectric layers, which are conductively coated and spirally wound with respect to the axis $y-y$, the connecting ends of the said layers passing to the two end plates a and b of sheet metal. Cup-shaped members c of the discharge cartridge are electrically connected to the said end plates, the said discharge cartridge consisting of an insulating tube i , spark-gaps e and a damping resistance w .

If for any reason a boosting voltage arises between the end plates a and b , the same is compensated by the spark-gaps e and the resistance w without overloading or puncturing the insulating material k of the condenser.

The number of the spark-gaps e has to be sufficiently great, so that the quenching or extinguishing effect of the multiple spark-gap is large enough to again extinguish the arc formed during the normal working voltage. Compared with similar known arrangements provided with protective spark-gaps outside the condenser, the arrangement according to the present invention possesses the advantage, that the protective means is located within the condenser or compound condenser (Fig. 2), so that the latter does not render necessary any particular protective measure, but forms itself a puncture-proof arrangement.

Fig. 3 is a view somewhat similar to Fig. 1, but in which are shown conductor strips m , leading from the conductive elements l along the interior of the conducting plates a and b and connected thereto by means of solder at n on the exterior thereof. There is also shown a spiral spring p within the discharger casting, the function of such spring being to maintain compression between the spark-gaps e , damping resistance w and the caps c . At q is shown a small metallic ring fastened on each cap for the purpose of holding the discharger in position within the condenser, this ring being sprung in a position in the recess in the end plates a and b to grip the dis-

charger in place. Fig. 4 represents a plan view of the condenser in which the conductor strips *m* lead to the points *n*, one set of conductive elements having terminals on the right-hand side, and the other set on the left-hand side, in agreement with Fig. 3. It will be noted that Figs. 3 and 4 illustrate the dielectric strips as having conducting layers on each face thereof in order that each strip 10 with its two layers constitutes a condenser in itself, Fig. 4 showing the condenser as being built up by winding up two of such strips into a hollow cylinder.

The constructions shown in Figs. 1 and 2 15 may be varied in many ways. The essential feature of the present invention consists in that each condenser or compound condenser is rendered puncture-proof by means of a discharge arrangement provided within the 20 same.

I claim:—

1. An electrical condenser having alternate dielectric and conducting layers of different polarity making up an annular body provided with an interior compartment enclosed by said layers, and a protective electrical discharge device disposed within said compartment having spaced electrodes respectively electrically connected with conducting layers 30 of different polarity.

2. An electrical condenser having alternate dielectric and conducting layers of different polarity making up an annular body provided with an interior compartment enclosed by said layers, and a protective electrical discharge device disposed within said compartment having spaced electrodes respectively electrically connected with conducting layers of different polarity, said discharge including a plurality of spark gaps arranged serially within said compartment.

3. An electrical condenser having alternate dielectric and conducting layers of different polarity making up an annular body provided with an interior compartment enclosed by said layers, and a protective electrical discharge device disposed within said compartment having spaced electrodes respectively electrically connected with conducting layers 50 of different polarity, said discharge device having associated therewith means for rendering the same self extinguishing.

4. An electrical condenser having alternate dielectric and conducting layers of different 55 polarity making up an annular body provided with an interior compartment enclosed by said layers, and a protective electrical discharge device disposed within said compartment having spaced electrodes respectively 60 electrically connected with conducting layers of different polarity and a damping resistance associated with said discharge device.

5. An electrical condenser having alternate dielectric and conducting layers of different 65 polarity making up an annular body pro-

vided with an interior compartment enclosed by said layers, metallic members at opposite ends of said body and respectively connected to conducting layers of different polarity and a protective electrical discharge device electrically connected between said metallic members and disposed within said compartment, said device having associated therewith means for rendering the same self extinguishing.

6. An electrical condenser having alternate dielectric and conducting layers of different polarity making up an annular body provided with an interior compartment enclosed by said layers, metallic members at opposite ends of said body and respectively connected to conducting layers of different polarity, a protective electrical discharge device electrically connected between said metallic members and disposed within said compartment, said device having associated therewith means for rendering the same self extinguishing, including a plurality of serially connected spark gaps and a damping resistance.

7. An electrical condenser having alternate dielectric and conducting layers of different polarity making up an annular body provided with an interior compartment enclosed by said layers, metallic members at opposite ends of said body and respectively connected to conducting layers of different polarity, a protective electrical discharge device electrically connected between said metallic members and disposed within said compartment, said device having associated therewith means for rendering the same self extinguishing, and a spring also bearing against said discharge device.

In testimony whereof I have signed my name to this specification.

EMIL PFIFFNER.
